UNITED STATES PATENT OFFICE.

JOHN LYNCH, OF RODNEY, MICHIGAN.

STUMP-PULLER.

No. 894,843.

Specification of Letters Patent.

Patented Aug. 4, 1908.

Application filed August 22, 1907. Serial No. 389,691.

To all whom it may concern:

Be it known that I, JOHN LYNCH, a citizen of the United States of America, residing at Rodney, in the county of Mecosta and State 5 of Michigan, have invented certain new and useful Improvements in Stump-Pullers; and I do hereby declare the following to be a full, clear, and exact description of the invention, such as will enable others skilled in the art to 10 which it appertains to make and use the same.

My invention relates to improvements in stump pullers, and its object is to provide the same with levers and tackle so constructed 15 that in starting the hoist the device will develop great power and slow movement, and later on can be operated more rapidly and with less power to complete the hoisting, and to provide the device with various new 20 and useful features hereinafter more fully described and particularly pointed out in the claims, reference being had to the accompanying drawings in which:—

Figure 1 is a side elevation of a device embodying my invention, adjusted as at commencement of the operation. Fig. 2, the same adjusted as at the end of the first stage 25 of the operation. Fig. 3, an enlarged detail of the hoisting bars and parts co-acting therewith; Fig. 4, a further enlarged detail 30 of a portion of the lower hoisting lever; Fig. 5, a plan view of the lower hoisting lever on a reduced scale, and Fig. 6, plan view of the upper lever.

Like numbers refer to like parts in all of the figures.

The frame of the device consists of a tripod, consisting of posts or legs 1, 2 and 3 pivotally attached near the top by means of a bolt 4. 40 The leg 1 being prolonged above the pivot for the purpose of attaching the various tackle blocks hereinafter described.

5 is a shackle surrounding the upper part of the leg 1 and supported by the upper ends 45 of the legs 2 and 3. To this shackle are pivoted pendulum rods 6 and 7 to support the respective hoisting levers 8 and 9 arranged one above the other. The lever 9 being supported by the shorter rod 7 and the lever 8 50 supported beneath the lever 9 by the rod 6.

Vertically disposed hoisting bars 10 extend downward at each side of the levers, being provided at the upper end with a connecting bolt 18 which adjustably engages a 55 series of hooks 19 in the upper edge of the lever 9. These bars are provided at the lower

end with a swiveled head 30 to which is attached one end of a chain 31 to engage the stump or other object to be hoisted, the other end of this chain being adjustably held 60 in a recess 32 in this head. These bars 10 are provided with hooks 14 at intervals to receive pins 13 and 17 arranged transversely of the lower hoisting lever and adjustably connected thereto. 65

To strengthen the lever 8, and provide a convenient support for these pins, curved brace bars 11 are attached to the respective sides of the lever 8; extend from the pivot thereof to near the middle of the lever, and 70 are rigidly attached thereto. To adjustably connect the said pins to these brace bars the pin 13 is inserted in a link 12 extending between the bars 11 and adjustably supported thereby by means of a pin 13^a in the upper 75 end of the link and adjusted in recesses 15 at intervals in the upper edges of bars 11. For high power I also provide a pin 17 extending transversely of the bars 11 and adjustably supported thereon by means of a link 16 pivoted 80 in the brace bars at its lower end, and supporting the pin 17 in its upper end. Whereby the pin 17 may be shifted to two different distances from the pivot of the lever, by tilting the link on its pivot, and is securely retained in each position. To operate 85 these levers, pulley blocks 20 and 22 are attached to the respective levers, and pulley blocks 21 and 23 are attached to the upper end of the leg 1, and a rope or cable 24 is roved 90 through these various pulleys in succession and thence extended downward through a block 25 near the bottom of one leg of the tripod, and the end of this rope extends horizontally therefrom to which end is applied 95 the power for hoisting the levers.

To support the upper lever 9 in elevated position after the first hoist has been made, a rope or cable 27 is attached thereto at one end and extends over a pulley 26 attached to 100 the upper end of the leg 1, and thence downward, being provided with a ring at its other end to engage a hook 29 on one of the legs of the tripod, and when so engaged the lever 9 is held in elevated position by said rope 27. 105

In operation, the device is adjusted as in Fig. 1 with the chain 31 attached to the object to be hoisted, and if only moderate power is required the pin 13 is engaged with one of the hooks 14 of the bars 10 and the 110 bolt 18 with one of the hooks 19 in the lever 9. These parts may be adjusted at various

distances from the pivots of the levers according to the power required. In extreme cases the pin 17 can be engaged with the upper hook 14, thus increasing the leverage of the lower lever to the maximum. After such adjustment, by applying power to the cable 24 the levers are hoisted at their movable ends, and will assume substantially the positions shown in Fig. 2 thus starting the stump 10 which at first requires the greatest amount of power and the slowest hoisting motion. The upper lever 9 is now secured in the substantially vertical position by engagement of the ring 28 with the hook 29, as in Fig. 2, thus 15 throwing out of action the upper lever, reducing the hoisting power, and increasing the rapidity of the hoisting movement. This movement may be increased and the power further reduced by shifting the link 12 away 20 from the pivot of the lever 8. The next hoist is now taken by means of the lever 8 alone, the bolt 18 traversing on the lever 9 and successively engaging the hooks 19 thereon, thus at each hoist holding all that is 25 gained, and raising the stump step by step as the lever 8 is successively operated. The pin 13 being shifted downward in the hooks 14 at each movement of the lever 8, and the link 13 shifted away from the pivot of the 30 lever as the power required decreases.

By this device I am thus able to develop great hoisting power with slow movement while starting the stump and later on decrease the power and increase the speed of 35 movement, which is impossible in many devices specially those depending on a screw for hoisting power or on levers having fixed adjustments.

What I claim is:

- 40 1. In a stump puller, the combination of a hoisting bar, two levers separately connected to said bar, a hoisting tackle common to both levers, and means for holding one lever immovable.
- 45 2. In a stump puller, the combination of a frame, two levers, a pulley block on each lever, opposing pulley blocks on the frame, a continuous rope or cable rove through all of the pulley blocks, and means for holding one 50 of the levers stationary while operating the other lever.
- 55 3. In a stump puller, two superposed and independently movable levers, hoisting tackle to operate the levers, means for holding the upper lever in elevated position, lifting bars arranged transversely of the levers, and means for adjustably connecting the bars to the respective levers.
- 60 4. In a stump puller, two superposed levers, means for simultaneously operating said levers, means for holding the upper lever in raised position while operating the lower lever, a series of hooks on the upper lever, lifting bars having a series of hooks, and a 65 transverse pin on the lower lever and adapted

to successively engage the hooks on the lifting bars.

5. In a stump puller, a tripod, two pendulum rods supported at the upper end by the tripod on upper lever supported by one rod, 70 and having a series of hooks in its upper edge, a lower lever supported by the other rod, and having a transverse pin adjustable thereon, a hoisting tackle common to both levers, a rope attached to the upper lever and 75 extending over a pulley on the tripod, means for securing said rope to hold the upper lever in elevated position, a hoisting bar at each side of the levers and having hooks at intervals, a bolt connecting the upper ends of said 80 bars and adapted to severally engage the various hooks on the upper lever, and a transverse pin adjustable on the lower lever, and adapted to successively engage the hooks on the hoisting bars.

6. In a stump puller, the combination of a lever, hoisting tackle to operate the lever, brace bars attached to the lever and extending parallel therewith, a hoisting bar at each side of the lever and each having a series of hooks, a link adjustable between the brace bars, a pin in the upper end of the link and adjustably engaging the brace bars, a pin in the lower end of the link and successively engaging the hooks in the lifting bars, 95 and means for supporting the lifting bars independent of the lever.

7. In a stump puller, the combination of a tripod, a tackle on the same, two pendulum rods supported by the tripod, an upper lever 100 and a lower lever each supported at one end by a respective rod, a pulley block on each lever, opposing pulley blocks on the tripod, a continuous rope or cable engaging the pulley blocks, means for holding the upper lever in 105 elevated position while the lower lever is separately operated, hoisting bars each having a series of hooks, a series of hooks on the upper lever, a bolt in the upper end of the hoisting bars and adapted to successively engage the 110 hooks on the upper lever, a pin adjustable on the lower lever and adapted to successively engage the hooks on the hoisting bars.

8. In a stump puller, the combination of a tripod having one long leg extending above 115 the other legs, a shackle surrounding the long leg and supported by the other legs, two pendulum rods supported by the shackle, an upper lever supported by one rod and having a series of hooks on its upper edge, a lower lever supported by the other rod and having brace bars attached thereto and extending beneath the same, a pulley block attached to each lever, opposing pulley blocks attached to the long leg of the tripod, a continuous 120 rope or cable engaging the pulley blocks to operate both levers, a rope or cable attached at one end to the upper lever and extending through a pulley block on the tripod, a ring 125 at the other end of the rope, a hook in the 130

tripod to engage and hold the ring, hoisting bars embracing the levers, a bolt in the upper end of the bars to successively engage the hooks in the upper lever, and a pin adjustably supported on the brace bars and adapted to successively engage the hooks in the hoisting bars.

In testimony whereof I affix my signature in presence of two witnesses.

JOHN LYNCH.
